UNITED STATES PATENT OFFICE.

BERT A. OLSON, OF MAYWOOD, ILLINOIS.

ELECTRICAL CONNECTION.

Application filed September 22, 1923. Serial No. 664,152.

To all whom it may concern:

Be it known that I, BERT A. OLSON, a citizen of the United States, and a resident of Maywood, county of Cook, and State of Illinois, have invented certain new and useful Improvements in Electrical Connections, of which the following is a specification.

This invention relates to novel improvements in electrical connections and has for 10 its principal object the provision of an improved construction of this character which will be highly efficient in use and economical in manufacture.

In order to make an electric connection 15 between a lead wire or extension and the source of supply, the lead wire or extension is usually provided with a plug having a threaded sleeve at one end adapted for threaded engagement in a socket and in 20 order to attach the plug to the socket it is necessary to turn the plug a number of times in a circumferential direction so as to bring about the threading operation of the sleeve and in turning the plug to bring about this 25 operation the lead wire or extension attached to the plug becomes twisted and curled and the twisting and curling of the lead wire or extension tears the covering of the same and cracks the insulation of the wire, in 30 other words, the turning of the plug acts upon the lead wire or extension to shorten the length of its service. It is one of the objects of the invention to provide a plug which can be mounted in the socket to make 35 the electrical connection without turning the plug in a circumferential direction and the construction of said plug is such that a permanent and positive connection is assured.

40 Other objects will appear hereinafter.

The invention consists in the combination and arrangements of parts hereinafter described and claimed.

The invention will be best understood by 45 reference to the accompanying drawings forming a part of this specification, and in which,

Fig. 1 is a side elevational view of an 50 electric connection embodying the invention;

Fig. 2 is a side elevational view of the same showing the plug in its threaded relation with a socket;

Fig. 3 is a sectional view of the invention 55 taken substantially on line 3—3 of Fig. 1;

Fig. 4 is a side elevational view of the

plug illustrated in Fig. 1 showing the outer shell, to be hereinafter referred to, removed therefrom;

Fig. 5 is a sectional view of the invention 60 taken substantially on line 5—5 of Fig. 3;

Fig. 6 is an end elevational view of the invention; and

Fig. 7 is a perspective view of an element 65 embodied in the invention.

Fig. 8 represents a cross section taken approximately on the line 8—8 of Fig. 3.

Referring to the drawings showing the preferred form of construction and with reference, especially to Fig. 2, the socket is indicated at 10 and comprises a central contact point 11 to which a conductor, not shown, is adapted to be fastened.

The socket 10 has the usual cavity 12 formed therein adapted to snugly accommodate a sleeve 13 having 70

its side walls provided with screw threads and to which a conductor wire, not shown, is adapted to be secured. As best illustrated in Figs. 1 and 3, 14 represents, as a whole, a shell having a central passage 16 formed 75

therein and terminating at its inner end into an enlarged cavity as indicated at 17. Ex- 80

tending through the central passage in the shell and adapted, as will presently appear, to have limited longitudinal movement with 85

respect to the shell is a plug 18, said plug and said shell being preferably formed of 90

non-conductive material. The plug 18, which, as will be observed, extends a con- 95

siderable distance beyond the shell has at 100

its inner end a contact point 19 bearing 105

against a conductor 20 in contact with a 110

connection 21 having an end 21' bent in parallel relation with the conductor and to 115

which a conductor wire indicated at 22 is 120

adapted to be secured. The plug 18 is sup- 125

ported through the medium of an arm 23 in- 130

set in a longitudinal recess 23' for the pur- 135

pose in the plug, said arm having an elongat- 140

ed slot 24 formed therein through which a 145

threaded member 25 is passed and threaded 150

into the plug as shown. The arm 23 is 155

provided at one end with an outwardly 160

bent portion 26 arranged in the cavity 17 165

and secured to the shell by means of a 170

screw member 26' and the opposite end of 175

the arm 23 is provided with a bevelled sur- 180

face 27, said arm being adapted to have 185

sliding arrangement with a conducting arm 190

28 to which a conducting wire 22' is con- 195

nected.

Secured upon the inner end of the plug

18 is a shell 29 made with a screw-threaded circumference 30 adapted to co-operate with the screw-threaded sleeve 13 and also made with a channel-shaped portion 30' fitting 5 the recess 23' and adapted to receive the arm 23. 31 is a tongue which is made with a screw-threaded portion 31' adapted freely to move outwardly and inwardly of the channel-shaped portion 30' in order to be 10 engaged with and disengaged from the screw-threaded sleeve 13. This tongue is mounted upon the inner end of a spring arm 32 slidable upon the arm 23 mounted at its forward end 33 upon the screw member 25. 15 Under this arrangement the arm 23 is slid- able within the channel-shaped portion 30' and upon the bottom 34 thereof, while the spring arm 32 is slidable limitedly upon said arm 23 and is made with an inward 20 deformation 35 adapted to co-operate with the bevel surface 27 of said arm 23, whereby when the plug is applied to the socket 10, the deformation 35 rising on the bevelled surface 27 will force the tongue in an out- 25 ward direction and thereby cause both the tongue and the shell 29 to engage the sleeve 13.

When the plug is to be withdrawn the shell is drawn endwise in a direction away 30 from the socket. The arm 23 being attached to the shell, is withdrawn with it; but the spring arm 32 under which the arm 23 slides, remains stationary until the spring deformation 35 rides over the bevelled portion 27 to allow the disengagement of the tongue 31 from the threads of the sleeve 13. The plug can then be readily withdrawn from the socket without any turning in a circumferential direction. To mount 40 the plug in the socket the sleeve bearing end of the plug is inserted into the socket bringing the contact point 19 into contact with the contact point 11 after which further forward pressure on the plug will cause 45 the shell 14 to move forward bringing the cam or bevelled surface 27 into contact with the deformation or curved tongue 35 raising the portion 31 so that the threads thereof engage the adjacent threads of the sleeve 50 13 and in this position the plug is positively secured into the socket without turning the plug in a circumferential direction.

From the description herein and with reference to the accompanying drawings it will 55 be seen that I provide an electric connection

having as a part thereof a plug which can be readily inserted and removed from a socket without damaging the conductor wires carried thereby and it is apparent that the plug can have universal application. 60

While I have illustrated and described the preferred form of construction for carrying my invention into effect, this is capable of variation and modification without departing from the spirit of the invention. I, 65 therefore, do not wish to be limited to the precise details of construction set forth, but desire to avail myself of such variations and modifications as come within the scope of the appended claims. 70

Having described my invention what I claim as new and desire to secure by Letters Patent is:

1. An electric connection including a shell member provided with an arm having a slot 75 therein and a bevelled end, a plug projecting from the shell and having a longitudinal recess therein, a threaded shell surrounding the plug and having a channel-shaped portion fitting said recess, said arm projecting into said channel-shaped portion and slid- 80 able therein, a screw member fixed to the plug for movably supporting the same upon said arm and passing through said slot for the purpose, a spring member slid- 85 able upon the arm and fixed to said screw member for movement with the plug and having a portion adapted to co-operate with the bevelled end of said arm, and a locking tongue carried by said spring member, sub- 90 stantially as described. 95

2. An electric connection including a shell member provided with an arm, a plug having a recess therein receiving said arm, means supporting said plug on said arm 95 for limited movement in relation to said shell member and arm, a cam-faced end provided on said arm, a threaded shell surrounding said plug and channelled to correspond with the plug recess, a spring mem- 100 ber slidable on said arm and co-operative with said cam-faced end thereon, means connecting the spring member for movement with said plug, and a threaded locking tongue carried by said spring member, sub- 105 stantially as described.

In testimony whereof I have signed my name to this specification.

BERT A. OLSON.
